UNITED STATES PATENT OFFICE.

HARLAN L. TRUMBULL, OF SEATTLE, WASHINGTON.

PROCESS OF PRODUCING ALKALIS FROM KELP.

1,238,600.

Specification of Letters Patent. Patented Aug. 28, 1917.

Application filed March 22, 1917. Serial No. 156,741.

To all whom it may concern:

Be it known that I, HARLAN L. TRUMBULL, citizen of the United States, residing at Seattle, in the county of King and State 5 of Washington, have invented certain new and useful Improvements in Processes of Producing Alkalies from Kelp, of which the following is a specification.

My invention relates to a process for the 10 production of alkalies from kelp by the employment of a method known as electrical endosmose and has for its object to afford a process whereby the referred to alkalies may be obtained more expeditiously and 15 cheaply than hitherto. A further object is to furnish compounds of potassium more valuable than those commonly derived from kelp.

The invention consists in the novel process 20 hereinafter described and claimed.

The apparatus by which my invention is attained, is illustrated in the accompanying drawings, in which —Figure 1— is a plan view, and —Fig. 2— is a transverse vertical 25 section through 1—1 of Fig. 1.

In the production of alkalies from kelp according to my invention the moist kelp, which may or may not be freshly harvested, (preferably after first being ground or cut 30 into pieces of conveniently small size) is pressed into the anode compartment of a suitable, divided-electrolytic cell wherein it makes intimate contact with and moistens a porous partition hereinafter described.

The container J, may consist of any material not already attacked by chlorin.

The anode D may consist of any electrode material which is relatively inert chemically in the presence of free chlorin, such as 40 amorphous carbon, graphite or cast magnetite.

The cathode G is of mercury and during electrolysis makes intimate contact with the above mentioned porous partition on the 45 opposite side from the kelp indicated by H. By electrolysis mercury is converted into an amalgam of alkali metals, which amalgam is decomposed in the presence of water

to furnish a solution of alkalies. This decomposition may be hastened by the use of contact agents such as graphite carbon, nickel or certain other solids. The decomposition of the amalgam may be effected either during the electrolysis or after its completion. In either case the resulting solution is a 55 mixture of alkalies containing a high percentage of caustic potash. The alkalies may be obtained in solid form by evaporating the solution to remove water and other volatile substances. 60

It may be remarked that the material which is used as a partition B to separate anodic and cathodic compartments may be of any composition so long as it possesses suitable rigidity, porosity, and insolubility. 65

I claim as my invention:

1. The process herein described for obtaining a mixture of alkalies, consisting firstly, of electrolyzing kelp in a divided cell with a mercury cathode, with the production of alkali metal amalgams, secondly in the treatment of the amalgams so produced with water to form a solution of alkalies, and thirdly, the production of solid alkalies by the evaporation of water and other volatile materials. 70

2. The process of obtaining alkalies from kelp by electro-osmosis, consisting in first removing the alkali metal ions to the mercury cathode to be therein discharged to 80 form amalgams, then decomposing the amalgams in the presence of water to produce alkalies and finally, evaporating the liquid therefrom.

3. The process of obtaining a solution 85 from kelp by first subjecting the kelp to an electro-osmotic action employing a mercury cathode, and then treating the amalgam produced thereby with water to afford a solution of alkalies containing caustic potash. 90

Signed at Seattle, Washington, this 17th day of March, 1917.

HARLAN L. TRUMBULL.

PIERRE BARNES,
W. W. MONTGOMERY,

Correction in Letters Patent No. 1,238,600.

It is hereby certified that in Letters Patent No. 1,238,600, granted August 28, 1917, upon the application of Harlan L. Trumbull, of Seattle, Washington, for an improvement in "Processes of Producing Alkalies From Kelp," an error appears in the printed specification requiring correction as follows: Line 36, for the word "already" read *readily*; and that the said Letters Patent should be read with this correction therein that the same may conform to the record of the case in the Patent Office.

Signed and sealed this 20th day of November, A. D., 1917.

[SEAL.]

R. F. WHITEHEAD,

Acting Commissioner of Patents.
